UNITED STATES PATENT OFFICE.

WILLIAM C. BURTCHE AND ELBERT M. GURNEE, OF KANSAS CITY, MISSOURI.

NAIL-DRIVER.

SPECIFICATION forming part of Letters Patent No. 404,166, dated May 28, 1889.

Application filed February 4, 1889. Serial No. 298,603. (No model.)

To all whom it may concern:

Be it known that we, WILLIAM C. BURTCHE and ELBERT M. GURNEE, of Kansas City, Jackson county, Missouri, have invented certain new and useful Improvements in Secret Nail Drivers and Sets, of which the following is a full, clear, and exact description, reference being had to the accompanying drawings, forming a part hereof.

Our invention relates to an improved nail driving and setting device; and it consists in the novel combination and arrangement of the various parts, as will be more fully hereinafter described and claimed.

In the accompanying drawings, forming part of this specification, and in which similar letters of reference indicate corresponding parts, Figure 1 is a vertical section of our improved device. Fig. 2 is a perspective view of the same, with top portion removed. Fig. 3 is a perspective view of the magazine, and Fig. 4 is a horizontal section taken on the line xx of Fig. 1.

The object of our invention is to provide a tool which drives and sets the nail by the same operation, and in constructing the same we employ a cylinder, B, which is formed with a central vertical bore, I, and communicating with this bore is a series of slots or apertures, B', cut in the cylinder B and extending nearly the entire length of the same. Through the bore I is passed the main shaft or tube D, upon which the cylinder revolves. The upper end of the tube D is threaded to receive an apertured knob or handle, a, and the lower end is threaded internally to receive the shouldered nut D'', by which it is secured to the cylinder B, and to prevent the tube or shaft passing down through said cylinder and to provide a uniform movement of the same, we form a ratchet-wheel, G, upon the shaft D, just above the upper end of the cylinder, said wheel having as many teeth as there are chambers in the magazine, and adapted to engage with the spring-pawl G', secured to the upper face of the cylinder B. The nut D'' is provided with the diverging slots e' e' in its lower part, said slots being adapted to receive the spring-knives or cutting-blades E, and to hold said cutting-blades securely we employ a nut, f, which, working

upon the nut D'', compresses the same to a certain extent, bringing the sides of the slots close together, which grip the ends of the knives and securely hold them in position. 55 The nut f also extends outward a sufficient distance to act as a shoulder to support the cylinder B and jacket C, which is placed around said cylinder.

When the cylinder, main shaft, and jacket 60 are in position, it will be seen that a magazine having a series of chambers is formed surrounding the main tube, said chambers being adapted to receive the nails to be driven, and to provide a means for supplying the 65 nails to said chambers we cut a slot or opening, C', in the jacket, and the portion of the main shaft held within the bore I is also slotted, as at D', to permit the nails to enter the bore of the main tube, where they are acted 70 upon by the driver F, carried within said tube, the slots C' and D' corresponding in size to the slots B' of the cylinder.

The bore of the lower portion of the main tube D is somewhat smaller than the upper 75 part, thus forming a shoulder, d', which limits the downward movement of the driver F, working in the main tube, the upper and lower portions of said driver being shaped to correspond with the upper and lower bores, 80 respectively. The upper and larger part of the driver F is provided with a lug, d, which works in a vertical slot, c, cut in the side of tube D, and is adapted to engage with the lug or projection p, carried by the knob a, 85 whereby the reciprocating movement of the driver is limited and prevents its being drawn out too far. The upper end of the driver F is provided with a handle, b, and just beneath said handle and surrounding the driver 90 is the metallic sleeve or collar e, which impinges against the knob a, and to prevent any injury the under side of said sleeve may be cushioned in any well-known manner. The jacket C is provided with the milled or 95 chased ring g, and the cylinder B is provided with a similar ring, g', said rings affording a convenient grip when operating the device. The construction of our device having been described, we will now proceed to describe its 100 manner of use and the operation of its various parts.

The combined nail driving and setting implement, constructed substantially as shown and described, is ready to receive the nails to be driven, and to feed said nails. The jacket C is moved around until the slot C' coincides with one of the slots B'. The nail h is then introduced into the chamber and the cylinder revolved the distance of one tooth of ratchet G, which brings another chamber opposite the slot C'. Another nail is then introduced, and so on. The operation is continued until the magazine is filled. When the magazine is filled and it is desired to drive and set a nail at any particular place, the driver F is drawn upward until the lug d strikes the projection p, and the lower portion of the driver being removed from the lower part of main tube and discharge-hole o the nail which is in the chamber opposite the slot D' passes into the main tube directly beneath the driver F. The nail is prevented from dropping through the discharge-hole o by the spring cutting-blades E, which are normally held together, as shown in Fig. 2, and form a single cutting-edge. The blades, in a closed position, are placed where the nail is to be driven, and by a slight blow upon the knob a are inserted the desired distance below the surface of the board. The driver F is now made to descend, and by hammering the same upon knob b the nail h is driven through the discharge-opening o, forces the blades E apart, and enters the wood. By one or two sharp blows the nail is set below the surface of the wood, and when the blades are withdrawn a smooth cut only is left, which can quickly be closed by a little soaking with water, thus leaving the head of the nail completely buried beneath the wood.

When another nail is to be driven and set, the cylinder is revolved until another nail-containing chamber is brought into coincidence with the slot D', and the operations are then again repeated. When the magazine is emptied, the jacket is moved around and the chamber refilled, as already described. The jacket C is held to the cylinder by frictional contact only, and usually revolves with said cylinder.

Having thus described the invention, what we claim is—

1. In a nail driving and setting implement, the combination of a main tube slotted at one side to receive the nails, the driver-bar carried within said tube, and the spring cutting-blades mounted in the lower end of the tube on each side of the driver-bar, substantially as and for the purpose set forth.
2. The combination, with the main tube provided with a slot to receive the nails, of the shouldered nut secured in its lower end and carrying the spring-blades E, the knob a, carrying projection p, and the driver F, working

in the main tube and provided with the lug d, adapted to slide in groove c and engage with projection p, substantially as shown and described.

3. In a nail driving and setting implement, the combination, with a main tube carrying a driver within the same and having in its lower end the spring-blades E, of a magazine secured upon said main tube and adapted to revolve around the same, substantially as shown and described.

4. The combination, with the main tube provided with a slot to receive the nails and carrying the blades E at its lower end, of a driver working in said tube and between the knives, a cylinder secured upon the main tube and slotted, as shown, and the jacket C, surrounding the cylinder B, substantially as shown and described.

5. In a nail driving and setting implement, the combination, with a main tube having different-sized bores and slotted to receive the nails, of a driver working in said tube and shaped to correspond with said tube, the knob a, secured to the main tube and carrying projection p, the lug d, formed on driver F and sliding in groove c cut in main tube, the ratchet-wheel G, cast upon main tube and adapted to engage with the spring-pawl G', the cylinder B, and jacket C, all arranged and adapted to operate substantially as shown and described.

6. In a nail driving and setting implement, the combination, with a main tube slotted to receive the nails, of the driver F, working in said tube, the cylinder B, secured to the main tube and turning on the same, the slotted jacket C, surrounding the cylinder B, the shouldered nut D'', slotted to receive the blades E, the nut f, working on nut D'', the ratchet G, formed upon main tube, and the spring-pawl G', adapted to engage with said ratchet, substantially as shown and described.

7. A nail driving and setting implement having a slitting device comprising a pair of blades at its delivery end, said blades being disposed upon each side of the driver-bar of the implement, whereby a slot in the material for the reception of the nail to be driven and set may be opened, substantially as described.

8. A nail driving and setting implement having the oppositely-located slitting-blades projecting from its delivery end, whereby a slit may be opened in the material for the reception of the nail to be driven and set, substantially as described.

In testimony whereof we affix our signatures in presence of two witnesses.

WILLIAM C. BURTCHE.
ELBERT M. GURNEE.
